UNITED STATES PATENT OFFICE.

SIEGFRIED MEYER, OF NEW YORK, N. Y.

ASH TRAY AND RECEPTACLE.

1,422,879.

Specification of Letters Patent. Patented July 18, 1922.

Application filed August 6, 1920. Serial No. 401,699.

To all whom it may concern:

Be it known that I, SIEGFRIED MEYER, a citizen of the United States, and resident of New York, in the county of Bronx and State 5 of New York, have invented certain new and useful Improvements in Ash Trays and Receptacles, of which the following is a specification.

The main object of this invention is to 10 provide means for supporting an ash tray at a number of convenient places in a room so that a smoker will not be obliged to get up from his chair and walk a distance to the tray. To accomplish this I provide an 15 ash tray support of novel design which may be attached to a chair, a window sill, a piano, or any other article of furniture or part of the room.

Another object is to provide a safety 20 means against fire by placing one of said supports next to a window, either attached to the frame or the sill, for then a smoker will deposit his match or cigar or cigarette butt in the tray and will not toss it through the 25 window and thus endanger the safety of the curtains, awnings or passersby in the street.

The above and other objects will become 30 apparent in the description below, in which like characters of reference refer to like-named parts in the drawings.

Referring briefly to the drawings, Fig. 1 is a view of the interior of a room, showing the application of my device.

Fig. 2 is a plan view of my complete de- 35 vice.

Fig. 3 is a side elevational view of the same.

Fig. 4 is a fragmentary sectional view 40 of my novel tray, showing the manner of its releasable attachment to the support.

Fig. 5 is a fragmentary sectional view of the support.

Referring now in detail to the drawings, 45 the numeral 1 represents the base plate of my support, having holes 2 therein for the passage of screws or other fastening means.

A horizontal stem 3 extends outward from the plate, and uprights 4 extend from the stem in spaced relation. Slotted resilient heads 5 are provided on the uprights, which 50 may be hollow. In place of the resilient heads springs of wire or bands may be provided, particularly for use upon upholstered furniture.

The tray or receptacle 6 may be of any de- 55 sired form, and is provided with hollow legs 7 having an interior form adapted to snap upon the heads 5 of the uprights 4, the tray thus being held securely and releasably. In order to remove the tray the same is simply 60 lifted up off the uprights.

The tray or receptacle 6 may also be used 65 as a depository for refuse such as fruit skins and pits, thereby eliminating the need of an additional receptacle.

In Fig. 1 exemplary applications of my de- 70 vice are illustrated, the same being shown attached to a chair 9 and the side of a piano 8. The position of attachment on the piano or chair may be selected at will.

In use the room is provided with a number of my attachments, say one on the window sill, one on the piano, if there is one, another on a chair, and others on various other articles and at other locations. Since the tray 75 and receptacle may be removed readily from one of the supports to another, these supports are permanently attached, and a number of trays may be used with a greater number of supports.

I claim:

A device of the class described comprising a base plate, a horizontal stem rigid to and extending rigidly therefrom, uprights extending in spaced apart relation from said 85 stem, resilient heads on said uprights, and a tray or receptacle having hollow elements to removably engage over said heads.

Signed at New York, in the county of Bronx and State of New York this 16th day 90 of June A. D. 1920.

SIEGFRIED MEYER.
